UNITED STATES PATENT OFFICE.

EDWARD W. POWERS, OF BOSTON, MASSACHUSETTS.

MUSICAL INSTRUMENT.

Application filed January 6, 1925. Serial No. 797.

This invention relates to stringed instruments and is intended more particularly as an improvement over the invention embodied in my co-pending application Serial No. 522,741, filed December 16, 1921.

Referring to the drawings wherein is shown merely for illustrative purposes one embodiment of my invention;

Fig. 1 is a plan view of a stringed instrument having the characteristics of a pianoforte of the so-called grand type showing portions of the case with the cover thereof removed;

Fig. 2 is a longitudinal section substantially upon the line 2—2 of Fig. 1;

Fig. 3 is a detail section upon the line 3—3 of Fig. 1 showing the manner of securing the ends of some at least of the bass strings to the piano frame;

Fig. 4 is a section similar to Fig. 3 taken substantially on the line 4—4 of Fig. 1, illustrating in detail the means for securing some of the lower treble strings to the frame;

Fig. 5 is a detail vertical section along a plane of the end of one of the shorter middle treble strings and substantially on the line 5—5 of Fig. 1;

Fig. 6 is a detail vertical section showing the resilient finger for supporting the upper treble string in the plane of the section line 6—6;

Fig. 7 is a detail vertical section on the line 7—7, Fig. 1, illustrating one type of supporting means for bass strings;

Fig. 8 is an enlarged detail side view of the end of one of the supporting fingers showing the manner of securing the strings to said finger; and

Fig. 9 is a plan view of the same.

It will be obvious from the following description that the invention applies to various forms of stringed instruments but, for convenience merely, it has been applied to a pianoforte of the grand type wherein a casing for supporting the various elements of the instrument is shown at 1. Within this casing are mounted keys 2 and an action shown in part at 3, Fig. 2, having hammers one of which is shown at 4 and other features well known to those skilled in the art but, as the action is to form no part of the present invention, no detailed or more complete description thereof is believed necessary.

Mounted within the casing 1 and secured thereto in any appropriate manner is a sounding board 5 which may be and preferably is of the usual construction.

Arranged adjacent to said sounding board is a plate 6 of substantially rigid construction embodying the usual plate head 7 bearing in the present example tuning pins 8, 8 to which the various strings are attached. The plate 6 also desirably includes a bearing bar 9 connected by appropriate struts 10, 10 with the plate head 7 and lower plate member 11. Carried by the plate 6 are the usual piano strings 12 including bass strings 12^a, lower treble strings 12^b, middle treble strings 12^c, and upper treble strings 12^d. Each of these strings is represented as secured at one end to the frame as, for example, by means of the aforesaid tuning pins 8. Desirably the opposite or tail ends of most at least of said strings are herein shown attached in such a manner as to permit a slight yielding of said tail ends laterally with respect to the face of said sounding board 5.

Obviously the mediums by which the yielding effect of said string tails is accomplished may vary materially but in the present example I provide, in certain instances, struts or fingers 13 arranged substantially parallel with the strings. To give the best results and greater freedom of action during said lateral vibratory movement or yielding action, the ends of said fingers or struts are fixed to the plate 6 at points approximately between the ends of the strings and desirably upon a marginal lip 14 constituting an integral part of the frame and extending therefrom beneath the tails of said strings. This arrangement of said fingers provides a more natural vibration of the strings or unisons as hereinafter described, also a more natural relationship between the vibrating unisons and sounding board which amplifies its tones. The reason for this relationship is that the severe resistance of the conventional plate is reduced, if not substantially eliminated, by instituting a condition of poise without reducing the longitudinal supporting ability of the plate. In other words the vibrations of the strings are sustained for the reason that the tail ends of said strings are supported so as to present a condition of natural poise, rather than by being supported by a plate

which severely resists activity. By thus freeing the vibrations the musical quality becomes far less metallic and has a desirable sustained singing tone.

5 The fingers or struts 13 may be attached to said marginal lip 14 in any appropriate manner but herein said fingers are properly positioned by means of dowels 15 and are rigidly secured in place upon said dowels by 10 screws 16. One or more of said screws and also one or more of said dowels may be employed according to the length and size of the fingers to be secured, the number of 15 said dowels being also consistent with the pressure to which the said fingers are to be subjected. For example in Figs. 3 and 4 which herein represent the fingers for supporting certain bass and some of the treble strings, the fingers are relatively long and 20 are consequently each provided with two screws 16. The fingers shown in Figs. 5 and 6 supporting the shorter middle strings and the treble strings respectively are of a lighter construction and, therefore, need be secured 25 by only one screw each because they are not called upon to sustain forces of such magnitude as must necessarily be exerted upon the fingers of lower and heavier strings.

30 The fingers 13 may, within the scope and purpose of the invention, be called upon to support one string or two or more strings as in the so-called "unisons" commonly used in pianos and the body of each finger may be proportioned with regard to width, 35 thickness and length so as to best produce the degree of resiliency or stiffness commensurate with its load and position relative to the sounding board as hereinafter explained.

40 Naturally where the strings are long and heavy as in the bass group the velocity of vibration is relatively low and hence the element of freedom at the tail is not of so great importance as in the upper groups where the velocity of vibration is high. In fact if too much freedom is allowed them 45 percussion will be lost. However some musicians may desire a "hard" bass whereas others would prefer one less hard and obviously these qualities may, within the scope 50 and purpose of the invention, be varied from the relatively inflexible tail to the most resiliency finger employed. In the present embodiment an arrangement is shown whereby 55 a variable degree of hardness of tone in the bass string will result. For example the first eight strings of the bass group 12^a are shown secured by pins 17 directly to the frame 11 and these eight strings produce 60 tones of maximum hardness.

Following the aforesaid eight bass strings in the ascension of the scale is a second group or series of strings or unisons which I have shown secured preferably by pins 18 to an

auxiliary plate 19 herein extending transversely of the entire second group of strings and said plate, in turn, may be carried by one or more, herein three, resilient fingers 20. The fingers 20 are, like the fingers 13, arranged substantially parallel with the 70 strings attached to the auxiliary plate 19 and these fingers may be and preferably are rigidly secured to the frame 14 at points between the extremities of the strings, thus providing, only in a lesser degree than the 75 individual fingers, a lateral freedom of movement not possible with the lower group of strings secured directly to the frame. It is, however, to be understood that the plate 19 is not limited to use with the specific 80 group of strings shown, nor is it in any wise limited to the number of strings attached to it or to the length herein shown.

85 Other bass strings or unisons may, as shown at 21 Fig. 1, be carried by individual fingers such as are shown in Fig. 3, the resiliency of which will be varied in proportion to the freedom of movement desired. It is, however, to be understood that the invention is not limited to the grouping of the 90 strings shown but any one form or any combination may be used to satisfy the demands of the trade or of individual musicians. When fingers or struts are called upon to support heavy bass strings the best results 95 may at times be secured by providing individual fingers for each string. At other times two or more strings may be carried by each finger and, in various treble groups where the lateral forces acting upon said 100 fingers are greatly reduced because of the reduced weight of the string body, unisons of three or more strings may be and preferably are carried by each finger.

105 There are numerous ways in which the various strings may be connected with and secured to their respective supports but desirably each supporting finger 13 and the auxiliary plate 19 are provided with a transverse shoulder or rib 22 against which 110 a bearing bar 23 is placed. The upper face of each bar is rounded where the strings engage it to prevent cutting of the strings. In Figs. 3, 8 and 9 I have shown one method of securing either one or two base 115 strings to its finger wherein the end of the wire is passed over the rounded surface of said bearing bar 23, thence downwardly and along the under face of the finger. At this point the end of the wire is given an upward turn passing through an obliquely inclined hole 24 to the free end face of the finger where it is turned laterally at 24' back of the downwardly extending portion 120 of said string which pinches said end firmly against the end face of the finger preventing any slipping thereof after the string is placed under tension. The end of said 125

string is inserted in a hole 25 extending lengthwise of the finger to prevent vibration thereof and to provide additional security against slipping. It will, however, 5 be obvious that in the actual stringing up of a piano the end of the string is first inserted in the hole 25 and afterward bent around the end of the finger and over said bearing bar.

10 When a unison of two or more strings each composed of a single strand of unwound wire is supported by one finger, the free end of the finger may be reduced in width to form vertical shoulders 26 (see Figs. 1 and 4). The two outer strings are desirably integrally formed from a single strand of wire doubled into a loop 27 and firmly held against the shoulders 26 by the tension upon the strings, with said loop 20 extending around beneath the reduced end of the finger, the free ends of said strings being attached in the usual manner to the tuning pins 8. The middle string of the series is preferably bent around the reduced 25 end between the shoulders 26 from within a hole 29 extending obliquely upward from the under side of the finger toward the free end thereof. The portion of said wire which extends along the under face of the 30 finger will lie inside of and be pinched by the loop 27 at 28 and this loop is generally the last to be placed upon said finger in the actual stringing operations. The acute bend of said wire where it enters said hole 35 29 and the pinching by the loop 27 effects a sure hold upon said middle string which prevents all slipping when tension is placed upon the strings.

The vibrations of the various strings produced by the striking of said strings with the hammers 4 may be transmitted to the sounding board in various ways. Desirably in this connection, means are provided to rigidly tie the free ends of said resilient 40 or yielding fingers 13 directly to said sounding board so that all lateral movements or vibrations of the strings will be transmitted directly through said fingers to said sounding board and amplified thereby. 45 These tying means may vary materially in form but preferably they are made adjustable as shown in Fig. 4 and include a screw-threaded rod 30 which depends from the end of said finger through an opening 50 31 in the lip 14 of the frame and into screw-threaded engagement with a sleeve 32 herein mounted in the sounding board 5. It will be apparent that either the rod 30 or the sleeve 32 may be rotated to effect 55 the desired adjustment between them but, for convenience, this rotation is confined to said sleeve which is accordingly rotatably mounted in said sounding board preferably within a bushing 33^a. The sleeve 32 60 extends through said sounding board and

has a check nut 34 arranged in screw-threaded engagement with the lower end of said sleeve and adapted to seat, preferably against a strip 35 secured to its face. The lower end of the sleeve 32 is suitably 70 formed, as for example as shown at 36, to have fitted thereto suitable turning means whereby said sleeve may be rotated within the sounding board to vertically adjust the rod 30. When rotation of the sleeve is 75 completed the nut 34 is screwed tightly against its seat on the strip 35 to lock said thimble against inadvertent or accidental rotation.

Unless extreme care is exercised in 80 forming the threads of the rod 30 and the corresponding threads of said sleeve 32 more or less looseness will exist between them and thus produce noises which would greatly interfere with the musical qualities 85 of the instrument. The above difficulty may be and herein is reduced by slitting said sleeve 32 at 32^a in two or more places to form gripping jaws 32^b. When the nut 34 is tightened the jaws 32^b of said sleeve 90 will be contracted against said screw 30 by action of the tapered interior of said bushing 33^a upon the complementary tapered head of said sleeve 32. The bushing 33^a is preferably flanged at 33^b which seats 95 upon a hard wood cap 33^c secured to the upper face of the sounding board to reinforce the same.

Because of the relation of the rod 30 to 100 said sleeve, any rotation of the latter causes said rod to be moved up or down according to the direction of rotation of said thimble, permitting a minute adjustment of the stress between the free end of said finger 13 and 105 said sounding board whereby perfect accord of action or movement of the two will result. The rod 30 may be connected directly with the end of the finger 13 in any desirable or appropriate manner but, for convenience, 110 said rod is secured to the bearing bar 23 and passes through a hole 37 formed in the end of said finger (see Fig. 4). By reason of the tension upon the string or strings resting upon said bearing bar 23 the latter will be 115 securely held in position against the shoulder 22 and the upper face of said finger, preventing displacement of said bearing bar or the development of undesirable rattling noises. Furthermore the bearing bar, 120 being connected by the rod 30 with said sounding board, will transmit the stresses produced by the deflection of said finger directly to the sounding board and thereby maintain the proper relation between said board and said finger.

125 It is expedient that the squared portion 36 of said sleeve 32 and nut 34 be readily accessible for adjustment and this is possible with most of the strings of the instrument, particularly where the strings are of con- 130

siderable length. In the upper treble group of strings, however, the fingers or struts 13, owing to the shortness of the strings, are brought very close to the head end 7 of the frame, also to the piano action and the supporting means for the lower edge of the sounding board, making access to said nut and squared sleeve portion exceedingly difficult if not impossible. Accordingly a different arrangement for adjustment in this case has been provided, as shown in Fig. 6, consisting of a bushing or thimble 38 mounted upon rather than extending through the sounding board and in a strip or strips of wood or other suitable material 39 secured to the upper surface of the sounding board. The thimble 38 is preferably held in non-rotary relation to the strip 39 and has screw-threaded engagement with a stem or rod 40 extending upwardly into engagement with the end of the finger 13 arranged directly thereabove. The rod 40 is provided with a polygonal portion 41 adapted to fit a wrench or other instrument for effecting the rotation of said rod within said thimble. A check nut 42 or other locking means may be provided for securing the rod in its adjusted position relatively to said thimble. The engaging portions of the fingers 13 and rod 40 may obviously be formed in various ways to permit relative rotary movement and in the present example I have shown the upper end of said rod conically formed at 43 for engaging a correspondingly shaped recess 44 in the underside of said finger.

In most instances, particularly where the wires forming the strings are of small diameter, the practice of connecting the strings 40 with the sounding board shown in Figs. 4, 5 and 6, is preferable for, in these instances, the fingers 13 can be made long enough and of sufficient resiliency to vibrate readily with the string when the same is hit with the hammer of the piano action and in such cases practically all of the vibrations of said strings will be transmitted through the rod and thimble from the extremity of said finger with a high degree of efficiency.

50 The fingers 13 may also be and preferably are varied in length and resiliency from both edges toward the center of the sounding board to correspond with the variations in the degree of lateral deflection of said board 55 from and to the points mentioned. Naturally the deflection at or near the middle of the board will be much greater than at or near the edges. Fig. 4, illustrating one of the fingers near the middle of the sounding board, is shown much longer than the finger of Fig. 5, which latter finger is located nearer to the edge of the board than the former and hence subject to less deflection. The finger illustrated in Fig. 6 shows still another reduction in length of body as well as

in diameter, this finger being located substantially at the edge of the sounding board where the lateral deflection is very slight as compared with the others.

Where the strings are extremely heavy or 70 even moderately heavy as in the case of bass strings, the fingers 13 are desirably materially heavier and possess greater rigidity owing to the greater lateral forces acting upon them, else too much freedom of vibration will result and percussion be lost. In such cases the transmission of vibrations through the free ends of the fingers is inadvisable because the rigidity of said fingers tends materially to restrict the normal 80 breadth of movement or free transmission to the sounding board of the vibrations of the strings.

It may at times be found expedient to provide a bridge or individual bridges for each 85 string or unison at a suitable distance from the ends thereof and in Fig. 3 such a bridge is shown for each bass string as indicated by the reference character 45. These bridges are arranged near but in no wise 90 connected with the fixed end of the fingers except through the string. The bridges 45 each desirably include a head 46 having one or more transverse string holes 47 which are 95 preferably formed in two sections 48 and 49 extending into the head from opposite faces and inclined with respect to the plane of the outer ends of said holes so as to communicate with each other near the center of the head and there form a bearing point 50 100 adapted to deflect the string passing through the hole sufficiently to maintain said string and bearing point always in contact when the string is under tension. The head 46 has a depending screw-threaded stem 51 105 passing through an opening 52 in the lip 14 of the frame and engaging, at its lower end, a sleeve 32 substantially similar to that shown in Fig. 4 hereinbefore described. Although adjusting and locking means for 110 said stem 51 similar to those in Fig. 4 have been shown it is to be understood that the invention is not limited to this form.

The velocity of vibration of the lower 115 heavy bass strings is relatively so low that any lack of resiliency in the supporting fingers or tails of said strings is not of any great consequence, but, as the velocity of vibrations increase in the ascending scale, this element of freedom at the tail ends of the 120 strings or unisons becomes of increasing importance.

The individual spring fingers arranged as herein described between the tail ends of the strings and the plate, make it possible to 125 provide the exact resiliency or normal balance required for each string and the elimination of the usual string tails between the bridge and the plate by tying the tails of the fingers directly to the sounding board 130

tends still further toward the accomplishment of the desired results mentioned.

It will be noted, by referring to Fig. 1, that the bass strings 12 overlap or cross 5 the tails of some of the treble strings and connect with the lower plate member near the middle longitudinal area of the sounding board. Consequently the bridges 45 of said bass strings will engage said sounding 10 board substantially in the region thereof where the maximum deflection of the board occurs and, inasmuch as said bass strings are in some cases rigidly and in other cases substantially rigidly secured to the plate, 15 and furthermore because the bass strings, by reason of their size and relatively low velocity of vibration, possess qualities of massive force, a substantially maximum stress or compressive action will be exerted 20 by said bass strings through their bridges and upon said sounding board.

The treble strings on the other hand, with their increasingly high velocity of vibration, will have a penetrating potency which requires 25 that peculiar freedom of action presented by the resilient finger and, therefore, assume a lesser part in the compression of the sounding board.

By reason of the board-compression being 30 assumed in a major degree by the plate through the bass strings, a more sensitive basis for sympathetic vibration or accord is made for the less forceful but more potent and free qualities of treble tone, presenting 35 broadened and balanced free relationship between the lower and upper qualities of tone tending materially toward a higher degree of rhythmic musical expression.

Having thus described certain embodiments 40 of my invention I desire it to be understood that although specific terms are employed they are used in a generic and descriptive sense and not for purposes of limitation, the scope of the invention being 45 set forth in the following claims.

Claims:

1. In a musical instrument, in combination, a frame, a sounding board, a string adjustably connected at one end and resiliently 50 connected at the other end to said frame, and means to tie said sounding board and the resiliently connected end of said string together.

2. In a musical instrument, in combination, a frame, a sounding board, a string adjustably connected at one end and resiliently connected at the other end to said frame, and means to rigidly tie said sounding board and the resiliently connected end 60 of said string together.

3. In a musical instrument, in combination, a frame, a sounding board, a string adjustably connected at one end and resiliently connected at the other end to said frame 65 and adjustable means to rigidly tie said

sounding board and the resiliently connected end of said string together.

4. In a musical instrument, in combination, a plate, strings stretched across said plate, substantially rigid means for securing 70 one end of each of said strings to said plate, means for resiliently supporting the opposite end of each string, a sounding board adjacent to said strings, and means to tie the resiliently supported ends of said strings to 75 said sounding board.

5. In a musical instrument, in combination, a plate, strings stretched across said plate, substantially rigid means for securing 80 one end of each of said strings to said plate, means for resiliently supporting the opposite end of each string, a sounding board adjacent to said strings, and adjustable means to rigidly tie the resiliently supported ends of said strings to said sounding board. 85

6. In a musical instrument, a plate, a sounding board, a series of strings stretched across said plate in a plane or planes substantially parallel with said sounding board, a tuning pin at one end of each string, resilient supports for the other ends of said strings adapted to allow said other string ends to vibrate laterally with respect to the face of said sounding board, and means including a post arranged between the movable ends of said resilient supports and said sounding board to transmit vibrations from said supports to said sounding board. 95

7. In a piano, in combination, a series of strings, tuning means at one end of each string, a sounding board, means to support the other ends of said strings in laterally yielding relation to said sounding board, and means including a post to rigidly and adjustably tie said laterally yielding string 100 ends to said sounding board to transmit vibration of said strings to said board.

8. In a musical instrument, in combination, a plurality of string unisons, individual securing means for one end of each 105 string of said unisons, means for unitedly yielding supporting the opposite ends of the strings composing each unison, a sounding board, and a post to transmit vibrations from the ends of said unison supports directly to said sounding board. 110

9. In a musical instrument, in combination, a plurality of string unisons, individual securing means for one end of each of the several strings of said unisons, common 120 means for yielding supporting the opposite ends of the strings composing said unisons, a sounding board and means positively connecting the yieldable ends of said string unisons with said sounding board to transmit the vibrations thereof to said board. 125

10. In a piano, in combination, a plate, a sounding board, a series of strings stretched over said plate, resilient means interposed between the tails of said strings and said 130

plate to maintain a condition of poise there-between and tension means connecting said tails directly with said sounding board.

11. In a stringed instrument, in combination, a plate, a series of strings stretched across said plate, means interposed between the tails of said strings and said plate adapted to permit lateral yielding of said tails without reducing longitudinal support, 10 a sounding board and means connecting the extremities of said string tails with said sounding board to transmit vibrations thereto.

12. In a stringed instrument, in combination, a plate, a series of strings stretched over said plate including some strings secured rigidly to said plate and others having lateral resiliency with relation to said plate, a sounding board, means connected 20 with said rigidly secured strings at a distance from their securing means to transmit vibrations of said strings to said sounding board and means located at the extremities of said resiliently mounted strings to transmit the vibrations of the latter directly to said sounding board.

13. In a piano, a plate, a series of strings stretched over said plate including a group of bass strings having their tails rigidly secured to said plate to produce a relatively hard tone, laterally resilient longitudinally rigid means secured to said plate adjacent the tails of a second group of said series of strings, said laterally resilient means having 30 a plurality of strings attached thereto and adapted to permit the tails of the strings attached thereto to yield laterally of said plate for the purpose of providing relatively softer tones than those of the said fixed bass 40 strings and laterally resilient individual unison-supporting elements for subsequent unisons of the ascending scale adapted to produce a gradually increased degree of resiliency between the said unisons and said 45 plate.

14. In a stringed instrument, a substantially rigid plate, a series of strings each adjustably secured at one end to said plate and laterally resilient means interposed between the tail ends of a group of said strings and said plate, said laterally resilient means including a transversely arranged member embracing the tails of all strings of said group and to which said string tails are secured and a plurality of resilient fingers each secured to said transverse member and to said plate.

15. In a stringed instrument, a substantially rigid plate, a series of strings each 60 adjustably secured at one end to said plate and laterally resilient means interposed between the tail ends of a group of said strings and said plate, said laterally resilient means including a transversely arranged member embracing the tails of all strings of said 65 plate.

group and to which said string tails are secured and a plurality of resilient fingers each secured to said transverse member and to said plate at a point between the ends of said strings and a line substantially parallel therewith.

16. In a stringed instrument, a substantially rigid plate, a series of bass strings each adjustably secured at one end to said plate, means for producing a softer tone in 75 one group of said bass strings than in another including a member extending transversely of the tails of said group and to which said tails are secured, and a plurality of resilient supporting fingers for said member secured to said plate between the ends of said strings.

17. In a stringed instrument, a series of strings, a resilient supporting finger for the tail of at least one of said strings, a bearing 85 member arranged near the free end of said finger, a sounding board, and a post connecting said bearing member with said sounding board.

18. In a stringed instrument, a series of strings, a resilient supporting finger for the tail of at least one of said strings, a bearing member arranged near the free end of said finger, a sounding board, and a post connecting 90 said bearing member with said sounding board adapted to maintain predetermined stress therebetween.

19. In a stringed instrument, a series of strings, a resilient supporting finger for the tail of at least one of said strings, a bearing 100 member arranged near the free end of said finger, a sounding board and means adjustably connecting said bearing member with said sounding board adapted to maintain a predetermined state of stress between the 105 free end of said finger and said sounding board, whereby the movements of said finger may be transmitted to said sounding board.

20. In a stringed instrument, a series of strings, a resilient supporting finger for the tail end of at least one of said strings provided with a transverse shoulder near the free end thereof, a bearing bar seated against said shoulder and engaged by said string, a sounding board, and means extending 110 from said bearing bar through the free end of said finger and into adjustable relation to said sounding board adapted to maintain said finger and said sounding board in predetermined stressed relation.

21. In a stringed instrument, a series of strings, resilient supporting means for the tails of said strings, said supporting means varying in degrees of lateral freedom, a sounding board, and means including an adjustable post to transmit vibrations directly from the tail ends of said strings to said sounding board.

22. In a stringed instrument, a series of string unisons, a resilient support for each 130

of said unisons, successive supports in said series possessing varying degrees of resiliency, a sounding board, and means directly to reproduce the oscillations of said supports 5 upon said sounding board.

23. In a stringed instrument, a series of tensioned strings, vibratory supporting fingers for the tails of said strings, and means to secure the ends of said strings to 10 said supporting fingers including cooperating grooves to maintain the extremities of said strings in pinched relation to a tensioned portion thereof.

24. In a stringed instrument, a series of tensioned strings, supporting fingers for said strings and means for securing said string ends to said fingers including an oblique hole and crossed grooves respectively to contain the end and a tensioned portion of a string 20 whereby to pinch and hold said end.

25. In a stringed instrument, a series of strings, vibratory supporting fingers for the tail ends of said strings having fixed ends lying between the planes of the ends of 25 their respective strings, a sounding board and means positively connecting the vibrating ends of said fingers with said sounding board to effect a perfect accord of action between said ends and said board.

30 26. In a stringed instrument, a series of strings each having a vibratory tail, a sounding board, and means including rigid connections to effect a perfect accord of action directly between said vibratory tail and said 35 sounding board.

27. In a stringed instrument, a series of strings each having a vibratory tail, a sounding board, and rigid connecting means to effect a perfect accord of action between 40 said vibratory tail and said sounding board including an internally threaded sleeve rotatably arranged in said sounding board, a threaded rod engaging the threads of said sleeve and connected with said string and 45 means for locking said rod and said sleeve against relative movement.

28. In a stringed instrument, a series of strings or unisons, a sounding board over which said strings are stretched, a vibratory 50 finger 13 to which the tail of each string or unison is attached and means including a rod 30 and a relatively adjustable sleeve 32 for maintaining predetermined stress between said sounding board and the free end 55 of said finger to effect accord of movement therebetween.

29. In a stringed instrument, a series of strings, a sounding board and adjustable means to effect substantial accord of action 60 between said strings and said sounding board including an internally threaded sleeve and a threaded rod engaging said sleeve and connected with at least one string.

30. In a stringed instrument, a series of 65 strings, a sounding board and adjustable

means to effect substantial accord of action between said strings and said sounding board, including an internally threaded sleeve adapted to be rotated in said sounding board, and a threaded rod engageable 70 with said sleeve and having connection with at least one string.

31. In a stringed instrument, a plate, a series of strings stretched across said plate, a resilient finger to yieldingly support the 75 tail end of at least one of said strings on said plate, a sounding board and means interposed directly between the end of said resilient finger and said sounding board to maintain said sounding board under stress. 80

32. In a piano, a plate, a sounding board arranged adjacent to said plate, a series of strings stretched across said plate, means for relatively rigidly securing said strings to said plate, means interposed between said strings and said sounding board adapted to maintain said board under maximum compression, a second series of strings stretched across said plate and laterally resilient means to support the tails of said second series of strings on said plate and to maintain said tail extremities and said sounding board in substantially natural vibratory accord. 85

33. In a piano, a plate, a sounding board 95 arranged adjacent to said plate, a series of bass strings stretched across said plate, means for securing the tails of said strings in substantially rigid relation to said plate, bridge means adapted to transmit from said strings a maximum pressure to said sounding board, a series of treble strings also stretched across said plate, laterally resilient supporting means for the tails of said treble strings, and means to maintain the 105 tail extremities of said treble strings and said sounding board in substantial vibratory accord.

34. In a piano, a plate, a sounding board arranged adjacent to said plate, a series of 110 bass strings stretched across said plate, means for securing the tails of said strings in substantially rigid relation to said plate, bridge means adapted to transmit from said strings a maximum pressure to said sounding board, a series of treble strings also 115 stretched across said plate, laterally resilient supporting means for the tails of said treble strings, and means to maintain the tail extremities of said treble strings and 120 said sounding board in substantial vibratory accord without impeding the natural deflecting movements of said board.

35. In a piano, a plate, a sounding board, 125 a series of strings stretched upon said plate, a group of said strings being rigidly secured thereto, others of said strings being resiliently secured to said plate, bridge means interposed between said rigidly secured strings and said sounding board tending to exert 130

maximum pressure upon the latter and means connecting said sounding board with said resiliently mounted strings tending to exert a limited pressure upon said sounding board and to maintain it and the extreme ends of the strings connected in substantially natural vibratory accord.

36. In a stringed instrument, a series of strings, a sounding board, resilient supporting means for the tails of some at least of said strings, means for effecting substantial accord of vibratory action between the resiliently supported tails of said strings and said sounding board including a contractible sleeve, a rod adjustably engaging said sleeve and means to contract said sleeve upon said rod.

37. In a stringed instrument, a series of strings, a sounding board, resilient supporting means for the tails of some at least of said strings, means for effecting substantial accord of vibratory action between the resiliently supported tails of said strings and said sounding board including an internally threaded contractible sleeve, a threaded rod to engage the threads of said sleeve, and means to contract said sleeve against said rod.

38. In a stringed instrument, a series of strings, a sounding board, resilient supporting means for the tails of some at least of said strings, means for effecting substantial accord of vibratory action between the resiliently supported tails of said strings and said sounding board including a threaded rod, a tapered split sleeve internally threaded to engage the threads of said rod and rotatable relatively to said rod, and means including a tapered bushing to contract said tapered sleeve upon said rod.

39. In combination with a string, a resilient supporting finger for said string, a sounding board, and adjustable connecting means between the free end of said finger and said sounding board including a rod attached to said finger, a split tapered sleeve having threaded engagement with said rod and means including said taper to contract and lock said sleeve in engagement with said rod.

40. A sounding board, a series of low velocity strings arranged to exert maximum lateral stress upon said sounding board, a second series of strings arranged to exert a minimum lateral stress upon said sounding board and means interposed between the latter series of strings and said sounding board adapted to maintain said latter series of strings and said board in substantial vibratory accord.

41. In a piano, a series of strings, a sounding board, a plate, resilient fingers interposed between said plate and the tails of said strings, said fingers having a tendency to relieve the tension upon said strings in

proportion to lateral deflection thereof, and means directly connecting the free ends of said fingers with said sounding board.

42. In a stringed instrument, a relatively rigid plate, a series of strings stretched across said plate, an auxiliary relatively flexible plate having the tails of at least a portion of the strings of said series secured thereto and constituting a flexible hitch line for said strings and resilient supporting means for said auxiliary plate arranged substantially parallel with said strings and secured to said rigid plate.

43. In a stringed instrument, a sounding board, a relatively rigid plate, a series of strings stretched across said plate, an auxiliary relatively flexible plate having the tails of at least a portion of the strings of said series secured thereto and constituting a continuous resilient hitch line for said strings, resilient supporting means for said auxiliary plate arranged substantially parallel with said strings and secured to said rigid plate, and bridge means interposed between said strings and said sounding board.

44. In a stringed instrument, a sounding board, a relatively rigid plate, a series of strings stretched across said plate, an auxiliary relatively flexible plate having the tails of at least a portion of the strings of said series secured thereto and constituting a resilient hitch line for said strings, resilient supporting means for said auxiliary plate arranged substantially parallel with said strings and secured to said rigid plate at points substantially intermediate of the ends of said strings, and individual bridge means interposed between said strings and said sounding board.

45. In a stringed instrument, a series of strings, resilient supporting means for the tails of said strings, said supporting means varying in degrees of lateral freedom and adapted to provide different degrees of softness of tone in different strings, a sounding board and means to transmit vibrations from said strings to said sounding board through the extremities of said supporting means.

46. In a stringed instrument, in combination, a plate, a series of strings stretched across said plate, string supporting means rigidly secured to the adjacent margin of said plate and arranged to flex laterally about a point near its base, said plate also being arranged to flex laterally and thereby cooperate with the lateral flexing of said means to provide a predetermined degree of lateral freedom of movement of said string without reducing longitudinal stability.

47. In a stringed instrument, in combination, a plate, a series of strings stretched across said plate, string supporting means supported upon the adjacent edge of said plate, said means and said plate having predetermined lateral flexibility cooperating

to provide a harmonic relationship between certain strings of said series.

48. In a stringed instrument, in combination, a plate, a series of strings stretched across said plate, string supporting means carried by said plate, said string supporting means and said plate cooperating to permit predetermined lateral freedom of movement of said strings without reducing longitudinal stability thereof.

49. In a stringed instrument, in combina-

tion, a plate, a series of strings stretched across said plate, string supporting means rigidly secured to said plate, said string supporting means and said plate cooperating to permit predetermined lateral freedom of movement of said strings without reducing longitudinal stability thereof.

In testimony whereof I have signed my name to this specification.

EDWARD W. POWERS.

CERTIFICATE OF CORRECTION.

Patent No. 1,703,167.

Granted February 26, 1929, to

EDWARD W. POWERS.

It is hereby certified that error appears in the printed specification of the above numbered patent requiring correction as follows: Page 1, line 72, for the word "frame" read "plate"; and that the said Letters Patent should be read with this correction therein that the same may conform to the record of the case in the Patent Office.

Signed and sealed this 9th day of April, A. D. 1929.

(Seal)

**M. J. Moore,
Acting Commissioner of Patents.**
